UNITED STATES PATENT OFFICE

GEORGE L. SMITH, OF BOSTON, MASSACHUSETTS

RADIATOR SHIELD

Application filed December 13, 1927. Serial No. 239,798.

This invention relates to a shield for automobile radiators and has for its object to provide a practical, yet simple and inexpensive device which may be easily and quickly attached at any location upon the front of a radiator and be adjusted to fit radiators of various widths and cover areas of various sizes.

Another object of the invention is to provide a means carried by the shield to secure the latter to the radiator, said means comprising a plurality of expandible and contractable members which may be inserted between the plates of the radiator and frictionally engage the sides of said plates.

The invention consists in a radiator shield as set forth in the following specification and particularly as pointed out in the claims thereof.

20 Referring to the drawings:

Figure 1 represents a front elevation of a radiator and its shell, a shield embodying my invention being mounted in position thereon.

25 Fig. 2 is an enlarged horizontal section through the shield as taken on the line 2-2 of Fig. 1.

Fig. 3 is an enlarged vertical section through the shield as taken on the line 3-3 of Fig. 1.

Fig. 4 is an enlarged vertical section through a portion of a radiator illustrating a means for securing the shield to the radiator.

35 Fig. 5 is an enlarged vertical section similar to Fig. 3, but illustrating a modified embodiment of the invention.

Like numerals refer to like parts throughout the several views of the drawings.

40 In the drawings, referring particularly to Figs. 1 to 4 inclusive, 6 represents a rail.

45 diator of conventional form and 7 represents a shell which is mounted upon said radiator and encloses the edge portions thereof. The radiator 6 may be of any well-

The radiator 6 may be of any well-known construction, but in the form illustrated in Fig. 4 said radiator is of a type which embodies therein a plurality of thin

50 horizontal plates 8 and a plurality of vertical

cal tubes 9 which project downwardly through said plates.

The shield of this invention embodies therein a body member 10 comprising a front wall 11 and rear wall 12, between which is a space 13 in which a plate 14 is located. The body member 10 is constructed of sheet material which is bent or folded at 15 to form grooves 16 constituting guideways in which the plate 14 is slidably mounted. It is evident that any suitable form of sheet material may be employed in constructing the body member 10 and plate 14, but I have found that a strong, tough, black paper or cardboard, which has been rendered impervious to moisture is very satisfactory.

The shield is secured to the front of the radiator 6 preferably to cover the lower portion thereof, as illustrated in Fig. 1, by a plurality of fastening devices 17, there being a fastening device located adjacent to each of the corners of the shield. The fastening devices extend through slots 18 provided in the body member 10 and plate 14 and comprise a head 19 and shank portion 20, the latter embodying therein a suitable expandible and contractable material which, upon engaging the sides of the plates 8 of the radiator 6, will frictionally engage said sides at 21 and firmly hold the fastening devices therebetween. 70 75 80

In attaching the shield to a radiator the plate 14 is pulled outwardly from within the body member 10 to form an extension therefor until the shield is sufficiently long to cover the entire width of the radiator. The shield is then attached to the radiator by forcing the fastening devices 17 which are carried by the body member and plate into the spaces between the plates 8 of the radiator. As the fastening devices are forced into the radiator their peripheries will frictionally engage the faces of the plates and firmly hold the shield to the radiator. In removing the shield from the radiator all that is necessary is to simply pull the fastening devices outwardly.

In Fig. 5 I have illustrated a modified embodiment of my invention in which a body 100

member 22 constructed of a single piece of sheet material and having a front wall 23 is bent or folded at 24 to form grooves constituting guideways 25 upon opposite edges of the body member, and a plate 26 also constructed of sheet material is slidably mounted upon the body member 22 within the guideways 25. The form of device illustrated in Fig. 5 is utilized in exactly the same manner as that illustrated in Figs. 1 to 4 inclusive and is attached in the same manner to the radiator 6. Each form of shield illustrated is so constructed that it may be attached to a radiator with the front and rear surfaces thereof reversed, and furthermore the front and rear surfaces of the slideable plate may be reversed within the body member to present either surface at the front of the shield. An entirely new front surface may, therefore, be presented to view at the front of the radiator if for any reason the original front surface becomes mutilated or defaced.

I claim:

- 25 1. A radiator shield having, in combination, a body member embodying therein front and rear walls and edge portions connecting said walls, and a plate slidably mounted between said walls and edge portions and constituting an extension for the body member, said slide also being reversible within the body member to present either face thereof at the front of the shield.
- 30 2. A radiator shield having, in combination, a body member of paper material and embodying therein parallel front and rear walls and provided with an opening extending through an edge thereof, and a plate of paper material slidably mounted between said walls and adapted to project outwardly through said opening and thereby constitute an extension for the body member, the latter also being adapted to be secured to a radiator with either its front or rear wall contacting therewith.
- 35 3. A radiator shield having, in combination, a body member constructed of a single piece of waterproof paper material and embodying therein front and rear walls and connecting edge portions, a plate of waterproof paper material slidably mounted between said walls and adapted to project outwardly beyond the edges thereof to constitute an extension for the body member, and means carried by the body member and plate to frictionally engage a radiator and hold the shield thereto.

In testimony whereof I have hereunto set my hand.

GEORGE L. SMITH.
